UNITED STATES PATENT OFFICE

2,637,356

STAKE POINTER

Charles D. Skates and Lucky I. Skates,
Roseburg, Oreg.

Application October 9, 1951, Serial No. 250,434

5 Claims. (Cl. 144—30)

1

This invention relates to improvements in pointers for stakes and the like, the primary object of the invention being to provide a device of this kind in which the stake to be cut to a point is thrust downwardly into the device between guides into engagement with and between cutters therein with the device resting upon the ground, so that the work of the operator in handling and pointing stakes is facilitated.

Another important object of the invention is to provide a simple and efficient device of the character indicated above which is readily adjustable for accommodating stakes of different sizes and for producing sharp or dull points on the stakes.

Other important objects and advantageous features of the invention will be apparent from the following description and the accompanying drawings, wherein, for purposes of illustration only, a specific embodiment of the invention is set forth in detail.

In the drawings:

Figure 1 is a front elevation, showing the access panel or door;

Figure 2 is a top plan view;

Figure 3 is a right-hand side elevation;

Figure 4 is a central, vertical, longitudinal section;

Figure 5 is an enlarged, transverse section taken through a cutter roller; and

Figure 6 is a fragmentary side elevation of Figure 5.

Referring in detail to the drawings, wherein like numerals designate like parts throughout the several views, the illustrated device comprises a vertically elongated, rectangular cross-section casing 7 having a box-like upper portion and a downwardly tapered lower portion, the casing 7 being formed of a front wall 8, a rear wall 9, and a base 10.

The front wall 8 comprises a perpendicular upper, stationary or fixed panel 11 and a lower panel 12 which is externally hinged at its upper edge, as indicated at 13, to the lower edge of the upper panel 11 to constitute an access door capable of being swung outwardly or forwardly to provide access to the interior of the lower part of the casing 7 and the cutter rollers therein. A handle 14 is provided on the door to facilitate opening and closing the same.

The rear wall 9 is composed of an upper, perpendicular panel 15 parallel to the upper panel 11 of the front wall 8, and terminates at its lower edge in a lower panel 16, similar to the door panel 12 of the front wall 8. The door panel

2

12 of the front wall and the lower panel 16 of the rear wall converge downwardly toward each other at similar acute angles corresponding generally to the slant to be cut on opposite sides or edges of stakes to be pointed.

The front wall 8 has rearwardly projecting flanges 17 extending vertically along the side edges thereof, these flanges being portions of angle irons 18 which include transverse flanges 19 which project laterally inwardly along the front side of the upper panel 11. The lower edge 20 of the upper panel forms the upper boundary of the door opening 21 which extends vertically downwardly from the edge 20 to the base 10 and transversely or laterally from the laterally inward edges 22 of the angle iron flanges 19.

The rear wall 9 has angle irons 23 on the side edges thereof like the angle irons 18, the flanges 24 of the angle irons 23 extending forwardly from the rear wall.

The base 10 comprises a horizontal top plate 25 from whose opposite side edges depend longitudinal flanges 26 whose lower edges 27 are designed to rest upon the ground 28 or other supporting surface, the inverted channel thus formed providing at its front and rear ends discharge or clean-out openings for the sawdust resulting from stake-pointing operations, the top plate 25 being formed with a sawdust-receiving opening 29 corresponding in area to the space between the lower ends of the lower panels of the front and rear walls 8 and 9, respectively, and between the side flanges thereof. The lower ends 30 of the angle irons 18 of the front wall 8 are fixed in suitable manner to the top plate 25 at the front end thereof.

The lower ends of the angle irons 23 of the rear wall 9 rest slidably upon the top plate 25 in spaced relation to the rear end of the top plate, and the lower part of the lower panel 16 of the rear wall 9 has an external angle iron bracket 31 fixed thereon which includes a horizontal arm 32 which extends rearwardly and slidably rests upon the top plate 25. The rear wall 9 is thereby mounted upon the base 10 for adjustment toward and away from the front wall 8 for accommodating stakes of different widths or cross-sections.

Means for locking the adjustment of the rear wall 9 includes a forwardly and rearwardly elongated slot 33 formed in the base top plate 25 through which bolts 34 depending from the bracket arm 32 extend, nuts 35 being provided on the bolts to lock the adjustment.

55 The front and back walls 8 and 9 are braced

in their proper erect positions by upper and lower pairs of horizontal rods or bolts 36 which traverse the upper wall panels 11 and 15 in substantial vertically spaced relation to each other and extend forwardly and rearwardly between the front and rear walls and are parallelly spaced from each other. As shown in Figure 2, the bolts of each pair are laterally spaced from each other at the same distance and are located close to the side flanges of the walls.

The front ends of the bolts or rods 36 are fixed relative to the front wall 8 by means of front and rear nuts 37 and 38 engaging the front and back of the front wall. The rear ends 39 of the bolts 36 are extended rearwardly of the rear wall and have thereon the front and rear nuts 40 and 41, which are engageable with the front and back of the rear wall, and which are adjustable along the rear ends 39 of the bolts 36 for locking the rear wall 9 in adjusted relation to the front wall 8. For example, to adjust the rear wall 9 rearwardly away from the front wall 8 from the position shown in Figure 4, the base bolts 34 are first loosened following which the rear nuts 41 are backed rearwardly along the bolt ends 39 the desired distance, whereupon the front nuts 40 are turned rearwardly along the bolt ends 39 until they engage the front side of the rear wall 9 and force the rear wall against the rear nuts 41. The base nuts 34 are then retightened.

The cutter rollers 43 are located in the lower tapered part of the casing 7 and along the facing sides of the lower panels 12 and 16. While seven cutter rollers 43 are shown along each of the lower panels 12 and 16, it will be understood that a greater or less number of cutter rollers may be used, if desired.

Each cutter roller 43 is composed of a relatively large diameter solid shaft 44 of generally cylindrical cross-section, having four similar and equally circumferentially spaced flat, longitudinal surfaces 45, the shaft 44 being only slightly shorter than the distance between the side flanges 17 and 24 of the front and rear walls 8 and 9, respectively, between which the rollers are located. The shafts 44 terminate at their left-hand ends in reduced pintles 46 which are journaled in the left-hand side flanges 17 and 24, and at their right-hand ends in reduced pintles 47 which are journaled through the right-hand side flanges 17 and 24 and have sprocket wheels 48 fixed thereon at points spaced laterally outwardly from the side flanges. As shown in Figure 1, some of the sprocket wheels are spaced laterally outwardly from others, in order that vertically adjacent pairs of the sprocket wheels can be operatively connected by means of sprocket chains 49, the lowermost cutter roller sprocket wheels being connected by other sprocket chains 50 and 51 to sprocket wheels 52 and 53 which are operatively connected by gear wheels 54 and 55 to the shaft 56 of a preferably electric motor 57 mounted on the ground or floor 28, whereby the cutter rollers 43 are all driven at the same speed with the front cutter rollers turning clockwise in Figures 3 and 4 and the rear cutter rollers turning counterclockwise. Alternatively, the positions of the rollers may be reversed, so that the front rollers rotate counterclockwise and the rear rollers clockwise.

The cutter rollers 43 include flat, longitudinal blades 58 which have beveled cutting edges 59 and ribbed, non-slip under surfaces 60 which engage ribs 61 on the flat surfaces 45, the blades being formed at intervals with transverse slots 62.

through which extend the shanks of studs 63 which thread into the surfaces 45 and have heads 64 to hold the blades in place. This arrangement permits the blades 58 to be adjusted crosswise of the rollers to extend the cutting edges tangentially or chordally beyond the periphery of the shaft 44 to increase or decrease the cutting depth of the blades. As shown in Figures 3 and 4, the cutter rollers 43 in the front and rear banks are uniformly and closely outwardly spaced relative to each other so that in action the blades 58 of adjacent rollers substantially overlap in cutting effect. The rollers in the two banks are also substantially on the same level.

In operation, the device having been adjusted for the size of stake to be pointed, a stake 66 is pushed downwardly in erect position through the open top of the casing 7 and its lower end engaged with the cutter rollers. The direction of rotation of the cutter rollers serves to move the stake 66 downwardly in engagement with the cutter rollers, so that the sides or edges of the lower end of the stake are tapered with a minimum of downward pressure being exerted by the operator. The bars 36 serve to guide the stakes 66 into accurate and uniform engagement with the cutter rollers 43 so that uniform points are formed on the stakes.

By proper adjustment of the machine, it may also be employed to cut points on pickets.

What is claimed is:

1. In a stake pointer, a casing having a pair of spaced walls, a base located at one end of said walls and extending therebetween, banks of rotary cutter rollers mounted on the laterally inward sides of said walls, said banks converging toward each other toward said one end, means for rotating said rollers together, the axes of said rollers extending crosswise of said walls, and parallel to each other and to the base, one of said walls being fixed to said base and the other wall being movable upon the base toward and away from said one wall, and means locking said movable wall in its adjusted position of movement.

2. In a stake pointer, a casing having a pair of spaced walls, a base located at one end of said walls and extending therebetween, one of said walls being fixed to said base and the other of said walls being movable upon said base toward and away from said one wall, banks of rotary cutter rollers mounted on the laterally inward sides of said walls, said banks converging toward each other toward said one end, and means for rotating said rollers together, a pair of guide bars extending between said walls, said guide bars being laterally spaced from each other and having one end thereof fixed to said one of said walls, the other ends of the guide bars having end portions extending through portions of said other wall, and means on said end portions and engageable with said other wall for adjusting said other wall toward and away from said one wall and locking said other wall in adjusted position.

3. In a stake pointer, a casing having a pair of spaced walls, a base located at one end of said walls and extending therebetween, banks of rotary cutter rollers mounted on the laterally inward sides of said walls, said banks converging toward each other toward said one end, and means for rotating said rollers together, the axes of said rollers extending crosswise of said walls, and parallel to each other and to the base, one of said walls being fixed to said base and

the other wall being slidably engaged with the base for adjustment toward and away from said one wall, bracket means on said other wall having an arm slidably engaged with said base, and releasable means acting between a portion of said base and said arm serving to free said arm for movement relative to the base and to lock said arm against movement relative to the base in an adjusted position of said other wall.

4. In a stake pointer, a base adapted to rest upon a supporting surface, a vertical casing rising from said base, said casing having spaced front and rear walls, said front wall being fixed to said base and said rear wall being movable on said base toward and away from said front wall, 15 releasable means securing the lower end of the rear wall to the base and permitting adjustment of the rear wall toward and away from the front wall, a bank consisting of a plurality of horizontal axes, vertically spaced cutter rollers extending across each of said walls at their facing sides, said banks of rollers converging downwardly toward each other, and means for rotating the rollers together.

5. In a stake pointer, a base adapted to rest 20 upon a supporting surface, a vertical casing rising from said base, said casing having spaced front and rear walls, said front wall being fixed

to said base and said rear wall being movable on said base toward and away from said front wall, releasable means securing the lower end of the rear wall to the base and permitting adjustment of the rear wall toward and away from the front wall, a bank consisting of a plurality of horizontal axes, vertically spaced cutter rollers extending across each of said walls at their facing sides, said banks of rollers converging downwardly toward each other, and means for rotating the rollers together, the rollers of the two banks being arranged to rotate in opposite directions to feed a stake downwardly in the casing in contact with the rollers.
